A. P. Wilson,
Cutting Shingles.

No 12,842.

Patented May 8, 1855.

UNITED STATES PATENT OFFICE.

ANDREW P. WILSON, OF PIQUA, OHIO.

SHINGLE-MACHINE.

Specification of Letters Patent No. 12,842, dated May 8, 1855.

To all whom it may concern:

Be it known that I, ANDREW P. WILSON, of Piqua, in the county of Miami and State of Ohio, have invented an Improvement in 5 the Machine for Cutting Shingles; and I do hereby declare that the following is a full and exact description thereof, reference being had to the accompanying drawings and to the letters of reference marked thereon.

10 To enable others skilled in the art to make and use my improvement, I will proceed to describe its construction and operation.

The machine is constructed as represented in the accompanying drawing.

15 The letters *a, a, a, a*, representing the side beams of the frame, *j, g*, cross pieces or ties on the under or lower side of the beams, *c, c* and *b, b*, cross pieces or ties on the upper side of the beams, constituting the frame- 20 work of the machine. On the inside of each of the side beams are iron slides *f, f*, fixed permanently to the beams, on which is to work the gate (*i, i, i, i*) containing the knife (*e*). The machine is to be placed in a horizontal 25 position.

The frame of the gate is constructed in the usual manner, as represented in Figure 2, of the drawing. The jaws of the gate (*s, s, s, s*) are of iron, and to project beyond the 30 sides of the gate a distance equal to the thickness of the iron slides, *f, f*, on which they are to work, thus holding the gate firmly on the iron slides, within the beams of the frame. The knife (*e*) which has two 35 edges, is flat on the upper side, with the proper thickness on the lower side in the center to insure strength, tapering with a gradual bevel to each edge, and is placed in the center of the gate. The doors (*t, t*), as 40 represented in Fig. 2 extend from the inside of each end of the gate, to within a short distance of each edge of the knife (*e*) and are supported by slats underneath, which are fastened to the sides of the frame of the 45 gate, as represented by *q, q, q, q*, in Fig. 4 by means of bolts or screws which pass through "long holes" in the slats.

On the upper side of the doors (*t, t*, Fig. 2) are placed slats *l, l, l, l*, running from 50 the ends of the gate toward the knife for the purpose of supporting the "block" as hereafter described.

On the under side of the doors (*t, t*, Fig. 3) are springs (*m, m, m, m*) extending a 55 short distance under the knife for the purpose of supporting the shingle while it is

being cut (*r* represents an edge view of the spring *m*). The box in which is to be placed the block to be cut, is in the center of the frame (*a, a, a, a*, Fig. 1) between the cross ties (*b, b*), as represented by *o, n, o*. The box is to be of sufficient size to admit any sized block that is to be cut. The inside of the box is to be faced with some kind of metal, to prevent wearing.

On the under side of the cross ties *c, c*, Fig. 1, are attached cleaners (*g, g*) (see Fig. 5) extending from the ties toward the knife and reaching down to the doors (*t, t*) with grooves (see Fig. 6) for the slats *l, l, l, l*, to pass backward and forward with the working of the gate. The doors (*t, t*) are regulated by means of the "long holes" in the slats (*q, q, q, q*, Fig. 4) underneath; thus lowering one end of one door and elevating the other end, to give the shingle the desired thickness and taper.

The other door, on the opposite side of the knife is regulated by the same means, as the first; but the end of the door of the first, that was elevated, to form the top of the shingle, in the second is lowered to form the butt or thick end. And the end of the first door that was lowered to form the butt of the shingle in the second is elevated to form the top. Place the block, out of which the shingles are to be cut, in the box *o, n, o*, Fig. 1 when it will rest on the knife (*e*). The power, which may be of any kind in use for propelling machinery, is attached to either 90 end of the gate, by means of a pitman or shaft.

Draw the gate to one end of the slides (*f, f*) when the block in the box *o, n, o*, will fall on the slats *l, l*, on the door (*t*); the door having been first regulated to form the proper thickness and taper to the shingle. The power continuing, causes the gate to pass back toward the other end of the slide; thus bringing the knife in contact with the block which is resting on the slats (*l, l*). The knife commences cutting the shingle, which passes under the knife, and is supported by the springs *m, m*, Fig. 3, until the knife passes under the cross tie *b*, and over the cleaner (*g*) which cleans the shingle from between the knife and springs, the knife having passed under the tie *b* permits the block again to fall upon the slats on the door *t* on the opposite side of the knife. 100 The gate in passing back again brings the knife in contact with the block again, which 105

having fallen on the door opposite to the first reverses the new shingle to be cut, taking the butt of the second shingle from the end of the block from which the top of the 5 first was taken; so on alternately. The knife having two edges, cuts two shingles at each revolution of the wheel.

What I claim as my invention, and desire to secure by Letters Patent, is—

10 The mode of adjusting the block out of which the shingles are to be cut, as set forth in the above specification, by means of the

adjusting slats (g, g, g, g , Fig. 4) underneath the doors, (t, t); and also the springs for supporting the shingle, as set forth above; 15 also the cleaners (g, g) for the purpose of cleaning the shingle from between the knife and springs and for the purpose of keeping the doors (t, t) clean from all substance that may fall on them.

ANDREW P. WILSON.
